United States Patent Office.

WILLIAM H. BROWN, OF LOWELL, MASSACHUSETTS.

Letters Patent No. 91,822, dated June 29, 1869.

IMPROVEMENT IN MACHINE-INDICATORS FOR CLOTH-MANUFACTURING, &c.

The Schedule referred to in these Letters Patent and making part of the same.

To all whom it may concern:

Be it known that I, WILLIAM H. BROWN, of Lowell, in the county of Middlesex, and State of Massachusetts, have invented new and useful Improvements in Machine-Indicators for cotton and woollen machinery; and I do hereby declare that the following is a full and exact description thereof, reference being had to the accompanying drawings, and to the letters of reference marked thereon.

The nature of my invention consists in providing a machine-indicator for cotton and woollen machinery, that will accurately give any measurement required, with but little hindrance to the user, being simple, durable, cheap, and useful.

To enable others skilled in the art to make and use my invention, I will proceed to describe its construction and operation.

Figure 1 represents a plan of my improved machine-indicator, showing its working-parts, how constructed and adjusted.

Figure 2 represents a front elevation of the same.

Similar letters, in the different figures, indicate corresponding parts.

In the construction of my improved machine-indicators—

a represents the base, on the top of which are secured the standards *b*, *c*, and *d*.

The standards *b* and *c* have bearings formed in the same, near their top, for the reception of the shaft *e*.

On the end nearest the stand *b*, is firmly secured the dial-gear *f*, by means of the nut *g*, and screw formed on the end of the shaft *e*.

The dial-gear *f* is formed with a dial, *h*, and gear *i*.

The dial *h* is divided and figured, indicating the number of yards of warp to the cut, the number of yards of yarn spun, or the number of yards of cloth woven; the gear *i*, its teeth corresponding in number with the figures on the dial *h*, thus each tooth in the gear *i* representing, on the dial *h*, one yard.

Near the outer rim of the dial *h* is the stop-pin *j*, which is firmly secured to the same. The object of this pin *j* is to operate against the shipper, stopping the machine when the desired number of yards of warp is dressed required in a cut.

Connecting with this dial-gear *i* is the pinion *k*, its length being sufficient to accommodate any-size dial-gear *i*, the number of teeth in the same ranging from twenty to one hundred, more or less, as the case may require, as the only change required in the indicator, to indicate a greater or less number of yards to a cut, is in this dial-gear *f*, thus enabling the operator to make the changes required in the same as he desires.

This pinion *k* is firmly secured to the shaft *l*, which is provided with bearings formed in the stands *b* and *d*.

Connected to the pinion *k* is the gear *m*, which connects with a worm or the driving-power.

n is the stationary pointer or finger.

My improved indicator being thus constructed, and its several parts adjusted in position, is then ready for use, motion being given to the different parts by means of the gear *m*. Thus, when the operator wishes to change the indicator, which is a common occurrence, more especially when applied to dressers, when a greater or less number of yards of warp is required to a cut, or when applied to spinning-frances, in spinning yarn of different degrees of fineness, or when applied to looms, in weaving cloth of different degrees of fineness and thickness, the operator is enabled so to do, at a moment's notice, by simply removing the dial-gear *f*, by aid of the screw *g*, and substituting in its place another dial-gear, *f*, having the required number of teeth to effect this change, which is also indicated on the dial *h*, with figures corresponding with the number of teeth in the gear *i*. Thus, in furnishing these indicators for the manufacturer's use, the required number of dial-gears *f* is connected with the same, to effect these several desired changes.

Thus, with the use of my improved indicator, the usual trouble experienced in the common ones now in use is entirely avoided, as when a change has to be made, in this case a new nest of gears has to be substituted, and also an entire separate dial, which not only results in inconvenience to the operator, and an unnecessary loss of time, but a great expense to the manufacturer, in being obliged to effect these changes by such an unlimited number of different sizes of gears, and a different and distinct dial for every change.

Thus it will be seen that my improvement, being simple, cheap in its construction, requiring but a little finish to put the same into working-order, compact, durable, and easily and quickly changed, far surpasses the common indicators now in use, and meeting the demands of the manufacturer.

What I claim as my invention, and desire to secure by Letters Patent, is—

The replaceable dial-gear *f*, in combination with the elongated pinion *k*, when arranged for the purposes herein described and specified.

WILLIAM H. BROWN.
